CLAIM

The ornamental design for a staple remover, as shown and described.

DESCRIPTION

FIG. 1 is a perspective view of a staple remover;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines and unshaded areas adjacent the solid lines in the drawings depict portions of the staple remover that form no part of the claimed design.

1 Claim, 6 Drawing Sheets
